(57) **CLAIM**

The ornamental design for a remote control, as shown and described.

DESCRIPTION

FIG. 1 is a perspective view of a remote control showing our new design;

FIG. 2 is a front view of the remote control.

FIG. 3 is a rear view of the remote control.

FIG. 4 is a left side view of the remote control.

FIG. 5 is a right side view of the remote control.

FIG. 6 is a top plan view of the remote control; and,

FIG. 7 is a bottom plan view of the remote control.

The broken lines in the figures depict portions of the remote control that form no part of the claimed design.
